FIG. 7.

INVENTOR.

Martha Grose Miller

BY
G. J. Ollanderet
ATTORNEY.

UNITED STATES PATENT OFFICE.

MARTHA GROVE MILLER, OF DENVER, COLORADO.

HOOK AND EYE.

SPECIFICATION forming part of Letters Patent No. 783,450, dated February 28, 1905.

Application filed September 27, 1904. Serial No. 226,230.

To all whom it may concern:

Be it known that I, MARTHA GROVE MILLER, a citizen of the United States of America, residing at Denver, in the county of Denver and 5 State of Colorado, have invented certain new and useful Improvements in Hooks and Eyes, of which the following is a specification.

My invention relates to a new and useful garment-fastening of the hook-and-eye type, 10 and more particularly to the class of devices adapted to fasten the plackets of skirts.

The discomfort, annoyance, and mortification caused by the accidental opening of the placket of the skirt, which only too frequently 15 and often without the wearer's knowledge occurs as the result of sudden strain put upon the garment by lifting the dress, stooping down, or other causes too numerous to mention, makes it imperative that the means employed for connecting the two flaps of the garment should not only be simple in construction and adapted to be readily fastened and unfastened, but should be especially designed to effectively withstand the strains to 20 which fasteners of this class are subject, at the same time being compact and neat in appearance.

The object of my invention is to produce a hook and eye for skirt-plackets in which the 25 various qualities enumerated in the preceding paragraph are combined. I attain this object by the mechanism illustrated in the accompanying drawings, in which—

Figure 1 represents the upper portion of a 30 skirt, the placket being in a partly-open condition; Fig. 2, an enlarged plan view of the two members comprising my device shown in place on the placket in the locked position; Fig. 3, a section taken along the line 3 3, Fig. 40 2; Fig. 4, a plan view of the hook member of the device, part of the tongue being broken away, drawn to a reduced scale; Fig. 5, a plan view of the eye member of the fastening drawn to a reduced scale; Fig. 6, a section taken 45 along the line 6 6, Fig. 2, looking in the direction of the arrow; and Fig. 7, a partial plan view of the hook member, showing a modified form of slot.

Similar reference characters refer to similar parts throughout the various views.

In Fig. 1 let C represent the upper portion of a skirt, the placket of which consists of the flaps A and B, which when in the closed position meet along a line E E. The fastenings, as mentioned heretofore, consist of two members 5 and 6, which being secured correspondingly along the opposite edges of the members of the placket and on the inside of the skirt will when hooked one into the other connect flaps A and B, as shown in Figs. 2 and 3. 60

The hook member 5 of my device being preferably made of spring metal consists of a flat base-plate 7, provided with a longitudinally-disposed elliptical slot 8 and an integral backwardly-extending downwardly-bearing reverse curvilinear spring-tongue 9. Perforations 10, located along the edge of plate 7, adapt member 5 to be secured to the garment by threads or other similar means. Tongue 9, the sides of which are right lined and parallel, extends from the extremity 7^a of the base-plate, with which when in its normal position it forms an acute angle α , in which the eye member reposes when in the locked position. Tongue 9 is in form composed of 75 two reversed curves c and d , the lower one, d , of which extends when in its normal position through slot 8 and below the lower surface of plate 7, while the free extremity 11 of the tongue projects upwardly above the upper 80 surface of the base. The width of tongue 9 in relation to the length of the minor axis of the elliptical slot is such that when in its normal position, as shown in Figs. 2 and 3, its edges will engage the converging edges of the 85 slot on both sides of its minor axis, thus forming four points of contact e , f , g , and h , which individually, as well as collectively, not only afford resistance against the strains to which the hook is subject when secured to the garment, but will most effectively prevent accidental unlocking of the fastening. 90

The eye member 6 of the fastening consists of a flat metal plate 12, provided with apertures 13, by means of which it is secured to 95 the garment, and an outwardly-extending integral loop or stirrup 14, forming the eye 15. Stirrup 14 is preferably made sufficiently light to allow thread to be wound around it in case it is desired to finish the member in conform- 100

ity to the color of the dress to which it is applied.

In securing the members 5 and 6 of the fastening to the flaps of the placket it is essential in order to insure proper fit of the garment that the extremity 7^a of plate 7 should extend to the very edge of the garment, while stirrup 14 of the corresponding eye member should project a short distance beyond the

10 edge of the opposite flap.

In fastening the garment the wearer takes hold of the plate 12 of member 6 to prevent tearing the skirt and, bringing the stirrup over and beyond plate 7, allows it to engage

15 the outer surface of the extremity 11 of tongue 9. On pulling the eye member backward its stirrup will before reaching its place in angle *a* consecutively engage and pass by the contact-points *e* and *f* and *g* and *h*, while

20 forcing the spring-tongue upward and out of engagement with the edges of slot 8. The force required to perform this operation will naturally depend on the intensity of the spring. When tongue 9 is in its normal position, its

25 sides engaging the edges of slot 8 at the four points *e*, *f*, *g*, and *h*, the downwardly-extending curved portion *d* will at the same time engage the cloth to which plate 7 is secured, as shown in Figs. 3 and 6. It will thus be ob-

30 served that the stirrup to be released from the hook will have to overcome the downward pressure of the spring-tongue at five distinct and separate points, reducing the chances of its becoming accidentally unfastened to a minimum.

35 In addition to this it will be noticed that when the stirrup if subjected to a sudden strain engages points *g* and *h* the tendency to lift the upwardly-curving portion *c* of the tongue will create a pressure at points *e* and *f*, which being reflected at the first-mentioned

40 points will afford additional resistance to the pressure exercised by the eye member.

The acute angle formed by plate 7 and tongue 9 will when the two members 5 and 6 are

drawn in opposite directions lessen the tendency of the eye member to lift the tongue off the plate, while in addition it reduces the height of the hook member to a minimum, which is of great importance in a device in which besides the features hereinabove described neatness of appearance and lack of bulk are the chief requirements.

I wish it understood that the shape of slot 8 may, if so desired, be varied, as shown in Fig. 7, in which a portion of the base-plate is represented provided with a diamond-shaped slot.

Having thus described my invention, what I claim is—

1. A hook and eye comprising in combination, an eye member and a hook member composed of a plate having a slot with converging edges and provided with a tongue extending over said plate and into said slot and having a plurality of points of contact with the converging edges of said slot.

2. A hook and eye comprising in combination an eye member and a hook member composed of a plate having a slot with converging edges and provided with a reverse curvilinear tongue extending over said plate and into said slot and having a plurality of points of contact with the converging edges of said slot.

3. A hook and eye comprising an eye member composed of a plate and an integral stirrup and a hook member composed of a plate having a slot with converging edges and provided with a reverse curvilinear tongue integral with and extending over said plate and into said slot and having a plurality of points of contact with the converging edges of said slot, substantially as described.

In testimony whereof I have affixed my signature in presence of two witnesses.

MARTHA GROVE MILLER.
